TUBE FORMING MACHINE

Adolf Haslauer, East Orange, N. J., assignor to
 Superior Tube Company, Philadelphia, Pa., a
 corporation of Pennsylvania

Application October 16, 1936, Serial No. 105,975

30 Claims. (Cl. 113—34)

This invention relates to an automatic machine for producing lock seam tubular formation from flat steel stock, such e. g. as cylindrical cathodes for use in thermionic valves or vacuum tubes.

This invention has for its general object to provide a machine for automatically forming, from flat sheet metal stock fed thereto, lock seam tubular structures for various purposes, and more especially for making cylindrical cathode elements of the lock-seam type similar to that shown in my United States Letters Patent No. 2,029,482, and, if desired, also providing such cathode elements with external positioning beads, similar to the disclosure of my co-pending application for

United States Letters Patent, Ser. No. 98,333/35.

This invention has for a further object to provide, in a machine for the stated purposes, a novel construction and relative arrangement of blank cutting and pre-forming dies, in combination with means to feed the blanks produced thereby onto a mandrel subject to the action of tube forming and seaming dies.

The invention has for another object to provide a novel construction and arrangement of co-operative tube forming and seaming dies together with means to effect properly timed and related operation thereof.

Other objects of the invention, not at this time more particularly enumerated, will be understood from the following detailed description of the same.

An illustrative embodiment of the invention is shown in the accompanying drawings, in which:

Fig. 1 is a front elevation of the cathode forming machine according to this invention; Fig. 2 is a side elevation of the same; Fig. 3 is a horizontal section, taken on line 3—3 in Fig. 1; Fig. 4 is a transverse section, taken on line 4—4 in Fig. 3; Fig. 5 is a horizontal section, taken on line 5—5 in Fig. 4; and Fig. 6 is a longitudinal section, taken on line 6—6 in Fig. 5.

Fig. 7 is a fragmentary cross-section, taken on line 7—7 in Fig. 5, showing the blank cutting and pre-forming dies and the blank feed means; and Fig. 8 is a perspective view of portions of these parts.

Figs. 9 to 15 inclusive are cross-sectional views showing the tube forming and seaming dies in their various correlated operative positions in carrying out the tube forming and seaming steps; and Fig. 16 is a fragmentary cross-sectional view of the finishing dies for completing the seaming operations.

Fig. 17 is a greatly enlarged perspective view

of the finished cathode element, which is the product of the machine.

Fig. 18 is a perspective view of strip-feeding mechanism appearing in Figs. 1 and 3.

Fig. 19 is a perspective view of cam structure appearing in Figs. 1 and 3.

Similar characters of reference are employed in the above described views, to indicate corresponding parts.

Referring to the drawings, the reference character 20 indicates the base of a suitable main frame 21 and associated removable frame head 23. Journaled in bearings 22 with which the main frame 21 and associated frame head 23 are provided is a transverse drive shaft 24, which may be driven from a source of power in any suitable manner, as, e. g., by a belt pulley 25.

Vertically reciprocable in guideways 26, with which said frame 21 is provided, is a stamp member 27. This stamp member 27 is provided, in connection with its upper end portion, with an upper cross-head 28 and a lower cross-head 29, which are respectively disposed above and below said drive shaft 24. Fixed on said drive shaft 24, so as to be revolved thereby, is an actuating cam 30 which is adapted to produce timed operative vertical reciprocation of said stamp member 27. Said cross-heads 28 and 29 are each provided with anti-friction rollers 31, with which engage the operative perimeter of said actuating cam 30, when the latter is revolved so as to reciprocate said stamp member 27.

Fixed upon the base 20 of frame 21 is a bottom die-block 32, and suitably affixed to the lower end of said stamp member 27 is an upper die-block 33. Said bottom die-block 32 is provided with up-standing dowel pins 34 which extend through corresponding openings or ways provided in said upper die-block 33, so that the latter is slidably moved thereon, and thus adapted to maintain an accurate register the subsequently described co-operative die elements with which the respective die-blocks are provided.

Suitably secured upon the bottom die-block 32 is the stationary die member 35 of a blank cutting and pre-forming die set. This stationary die member 35 is provided in its upper face with a longitudinally disposed blanking die formation comprising a transversely convex die portion 36 bounded on its left hand side by a vertical side wall adapted to form a stop shoulder 37, and on its right hand side by a vertical side wall which is formed along a portion of its length to provide a somewhat downwardly offset shearing or cutting edge 38 having an outwardly and downward-

ly extending chamfer 39 (see Fig. 7). Formed in connection with the stationary die member 35 to project from its convex die portion 36, in proper location, are one or more transversely extending male beading die portions 40. Suitably affixed to said upper die-block 33 is the movable die member 41 of said blank cutting and pre-forming die set. This movable die member 41 is provided in its bottom face with a longitudinally disposed blanking die formation comprising a transversely concave die portion 42 corresponding to the convex die portion 36 with which it is to cooperate. One longitudinal edge of said die portion 42, as the edge 43, constitutes a shearing or cutting edge adapted to cooperate with said shearing or cutting edge 38 of the stationary die member 35. Formed in connection with the movable die member 41, in proper location, are one or more transversely extending female beading die portions 44 adapted to cooperate with said male beading die portions 40 of said stationary die member 35.

Means are provided for automatically feeding sheet metal stock to and between said blanking and pre-forming dies 35 and 41. Preferably the sheet metal stock is in the form of a metal strip of a width corresponding to the length of cathode element to be produced, said strip being fed from a roll endwise across the stationary die member 35. This stock feeding means is subject to more or less variation in form and arrangement, but illustrative of one practical embodiment thereof, the same is herewith shown to comprise a guideway 45 through which the stock strip 46 is fed to advance its free end transversely across the stationary die member 35. The means for gripping and advancing the stock strip 46, comprises a slideway 47 connected with the machine frame, in which is reciprocably mounted a carriage 48. Fixed on the carriage 48 is a gripper means 49 having a projection 49a adapted to automatically grip and propel forward said stock strip on inward movement of said carriage 48, but to release and slide freely back along the stock strip on outward or retractive movement of said carriage 48. The means for producing properly timed movements of said carriage 48 comprises a bell-crank 50 which is pivoted to an extension of the machine frame. The downwardly extending arm 50' of said bell-crank 50 is pivotally connected to the carriage 48, while the inwardly extending arm 51 of said bell-crank is provided with a bifurcated end in which is engaged a tongue 52 which is affixed to and which moves up and down with the upper die-block 33. When the upper die-block 33 rises, on the upward or recovery movement of stamp member 27, said tongue 52, by its engagement therewith, swings upward bell-crank arm 51 and consequently swings inwardly 60 the bell-crank arm 50, thus producing an inward movement of carriage 48 so that the stock strip is gripped and propelled forward while the blanking and preforming die members are separated. When the upper die-block 33 descends, on the operative downward movement of the stamp member 27, said tongue 52 imparts a downward swinging movement to bell-crank arm 51, and consequently swings outwardly the bell-crank arm 50, thus retracting the carriage 48 and gripper means 49 to normal initial position ready for a succeeding strip stock feeding operation. The reference character 53 indicates a mandrel which extends longitudinally and outwardly between the bottom and upper die-blocks 32 and 33. Said mandrel 53 extends slidably through the

stationary die member 35 of the blanking and pre-forming die set, and its free outwardly extending portion lies in a plane slightly below the plane of the die portion 36 of said stationary die member. Means are provided for longitudinally reciprocating the mandrel for purposes subsequently to be mentioned. This means comprises a guideway 54 mounted on the frame base 20 behind the bottom die-block 32, said guideway having a channeled way in which a slide-piece 55, 10 is reciprocably slideable. The rear end of said mandrel is suitably affixed to said slide-piece 55. The means for producing properly timed reciprocation of said slide-piece and the mandrel carried thereby, comprises a transverse counter-shaft 56 journaled in bearings 57 which project from the main frame 21. This counter-shaft 56 is driven from the drive shaft 24 by chain and sprocket transmission means 58, or by any other suitable kind of transmission means. Mounted 20 on said counter-shaft 56 is a raceway cam 59. Pivotally supported from a bracket 60 on frame base 20 is an oscillatory lever 61, the lower end of which is pivotally connected with said slide-piece 55. Said lever 61 is provided with a roller 25 stud 62 which operatively engages the raceway 59a of cam 59, whereby said lever is oscillated to produce properly timed back and forth movement of said slide-piece and the mandrel carried thereby. 30

Means are provided for discharging a blank, after the same is cut and formed by the blanking and pre-forming dies, from the latter dies onto the mandrel subject to the operation of the tube forming and seaming dies of the mechanism. 35 This means comprises a push-piece 63 having depending fingers 64 to engage the rearward end of a formed blank (see Fig. 8) and, upon operation of the push-piece, thereupon push said blank forwardly off of the die member 35 and onto the 40 mandrel 53. The means for producing properly timed reciprocation of said push-piece 63, comprises a second slide-piece 65 movable in another longitudinal channeled way with which the guideway 54 is provided. Said push-piece 63 is suitably affixed to said slide-piece 65. Mounted on said counter-shaft 56 is a second raceway cam 66. Pivotally supported by a bracket 67 on frame base 20 is another oscillatable lever 68, the lever end of which is pivotally connected with the slide-piece 65. Said lever 68 is provided with a roller 50 stud 69 which operatively engages the raceway of cam 66, whereby said lever is oscillated to produce properly timed back and forth movement of slide-piece 65 and the push-piece 63 carried 55 thereby. 45

Arranged forwardly of the blanking and pre-forming die set are the tube forming and seaming dies. Mounted on the bottom die-block 32, to extend inwardly from the left side of the latter toward said mandrel 53 is a housing 70. Fixed on said die-block 32 between the mandrel 53 and the inner end of said housing 70 is a supporting block 71. In like manner, mounted on the bottom die-block 32, to extend inwardly from the right side of the latter toward said mandrel 53 is a housing 72, and fixed on said die-block 32 between the mandrel 53 and the inner end of the housing 72 is a supporting block 73. 65

Adjustably mounted on the respective housings 70 and 72 so as to be positioned in opposition to each other, respectively on opposite sides of the mandrel 53 are blank positioning and holding jaw-plates 74 which are slidably movable in ways 75 provided in the tops of the respective housings 75

10 and 12. Each jaw-plate 74 is provided at its rearward end with an upstanding lug 76 having an internally screw-threaded opening engaged by an adjusting screw 77. Fixed on each housing 5 10 and 12, behind the jaw-plate mounted thereon, is a bearing 78 for rotatably mounting the associated adjusting screw 77 in such manner that the same may turn while being held against axial movement. Each jaw-plate 74 is provided 10 at its free end portion with an undercut blank 15 engaging shoulder 79 having, at the end thereof toward the blanking and pre-forming die set, an upwardly inclined guide-in portion 80. When the blank B is discharged from the stationary die 15 member 35, for deposit in overlying relation to the mandrel 53, its leading end engages the guide-in portions of the shoulder 79 of the jaw-plates 74 so as to be downwardly deflected for passage beneath said shoulders 79 and between the ends 20 81 of said jaw-plates, thus positioning the blank across the mandrel and holding the same subject to the initial action of tube forming and seaming dies. The jaw-plates 74 are individually adjustable relative to the axis of the mandrel 53 25 so that the blank, as held therebetween, may be properly positioned to produce, when initially bent, a longer extension or wing on one side than on the other, thus providing a disposition of the stock of the blank which, upon initial bending 30 will permit of the proper formation of the laps and interlock of the seam which completes the cylindrical tubular cathode.

Arranged for vertical reciprocation beneath the mandrel 53 is a secondary stamp member 35 82, the same being slideable in a vertical way 83 provided in the bottom die-block 32. At its lower end said secondary stamp member 82 is provided with a laterally offset foot-piece 84 which normally stops against the frame base 20. A spring 40 actuated plunger 85, which is mounted in connection with the bottom die-block 32, bears yieldingly downwardly upon said foot-piece 84 to normally return said secondary stamp member 82 to downwardly retracted normal initial position. 45 At its upper end, said secondary stamp member is formed with an upwardly projecting die-head 86 of reduced width, and having at its extremity a concave die-surface 87 to conform to the cylindrical surface of the cathode tube to be formed. 50 At the juncture of said die-head with the secondary stamp member 82 and along the left hand side of the latter is a chamfered shoulder 88, the purpose of which will subsequently be explained. At the juncture of said die-head with the secondary stamp member 82 and along the right hand side of the latter is a shoulder 89, the purpose of which will likewise be subsequently explained. 55 The means for producing properly timed actuation of the secondary stamp member comprises a lever 90 pivotally connected with a fulcrum bearing 91 beneath the frame base 20. A slide-piece 92, vertically slideable through said frame base 20 is operatively engaged by the forward end portion of said lever 90, and is disposed to exert, at proper times, an upward thrust upon said secondary stamp member 82. A plunger 93 is mounted for vertical movement through a guide member 94 disposed beneath the counter-shaft 56, and so that its lower extremity bears operatively upon the rearward end portion of said lever 90. The upper end of said plunger 93 is provided with a nosing 95 which is operatively engaged by an actuating cam 96 carried and rotated by said counter-shaft 56.

75 Suitably affixed to the upper die-block 33 is a

bending die 97, provided in its lower face with an inverted U-shaped die-recess 98 adapted to straddle the mandrel 53, when lowered by the operation of stamp member 27, so as to initially bend the blank B over said mandrel. 5

Slidable in the housing 70 is a spring returned slide block 99 which carries a left-hand seam lap forming die 100. In like manner, slidable in the housing 72 is a spring returned slide block 101 which carries a right-hand seam lap forming die 10 102. Also slidable in said housing 70 is a spring returned slide block 103 which carries a seam lock forming die 104, this latter die underlying said left hand seam lap forming die 100. The slide blocks 99, 101 and 103 are respectively provided at their outer ends with nosings 105 to receive the engagement and thrust of actuating cams whereby the several dies carried by said slide blocks are caused to operate in properly timed relation. Mounted in bearings 106 connected with frame 21 is a left hand lay shaft 107. This lay shaft 107 is driven from said counter-shaft 56 by suitable intermediate gearing 108. Fixed on said lay shaft 107 is a suitably shaped cam 109 for engaging and actuating the slide-block 99 and its die 100, and also fixed on said lay shaft 107 is another suitably shaped cam 110 for engaging and actuating the slide-block 103 and its die 104. Mounted in bearings 111 connected with frame 21 is a right hand lay shaft 112. This lay shaft 112 is also driven from said counter-shaft 56 by suitable intermediate gearing 113. Fixed on lay shaft 112 is a suitably shaped cam 114 for engaging and actuating the slide-block 101 and its die 102. 35

Affixed to the slide-block 99 which carries the left-hand seam lap forming die 100 is a push-piece 115 adapted to be reciprocated with the slide-block 99. The free end portion of this push-piece 115 extends through a passage 116 which 40 is provided therefor in the supporting block 71, and said free end portion is provided with a chamfered deflector portion 117. Said push-piece 115 cooperates with the secondary stamp member 82, as will subsequently appear. 45

Affixed to the slide-block 101 which carries the right-hand seam lap forming die 102 is a second push-piece 118 adapted to be reciprocated with said slide-block 101. The free end of this push-piece 118 extends through a passage 119 in the 50 supporting block 73, so that it may also properly cooperate with the secondary stamp member 82 in the manner hereinafter explained.

Mounted on the bottom die-block 32 beyond the tube forming and seaming dies is female 55 finishing die 120, and carried by the stamp member 27 for cooperation therewith is a male finishing die 121.

The heretofore described movable die member 41 of the blank cutting and pre-forming die set, 60 the bending die 97 and the male finishing die 121 are each provided with spring pressed yieldable work engaging plungers or grippers 122 which, upon operation of these dies, engage and grip the work so as to hold the same against accidental 65 shifting during the various forming operations in which these dies take part.

The above description of the various mechanisms making up the machine will in part at least explain the operation thereof so far as the 70 transmission of power to the various die elements is concerned. The operation of the said die elements per se is as follows:

As the stamp member 27 rises, the stock feeding means advances the strip 46 thereof over 75

the face 36 of die member 35 until its free end is stopped against the stop shoulder 37. In this position an end portion of said strip 46 overlies the die face 36 and the shearing or cutting edge 38. Timed operation of the machine thereupon causes the stamp member 27 to descend, thereby carrying movable die member 41 downward toward die member 35. The shearing or cutting edge 43 of die member 41, in passing the cutting or shearing edge 38 of die member 35 shears from the strip a blank. Completion of the downward movement of die member 41 stamps this blank into a preliminary transversely concavo-convex shape, while at the same time the operating male and female beading die portions 40 and 44 emboss the blank with the transverse beads 123. These operations being completed, the stamp member 27 is retracted or raised to separate the die member 41 from die member 35. While said die members 41—35 are separating, and before the next advance movement of the stock strip 46, the cam 66 is timed to produce a quick forward and back movement of the push-piece 63, whereby its fingers 64 engage the rear end of the formed blank B to quickly push the same endwise off of die member 35, and into engagement with the holding jaw-plates 74, whereby the blank B is deposited above and across the mandrel 53 (see Figs. 7, 8, and 9). As the stamp member 27 begins a succeeding downward movement, the cam 96 operates lever 90 to raise the secondary stamp member 82 to position its die-head 86 in supporting relation to the underside of mandrel 53, whereupon continued descent of stamp member 27 carries the bending die 97 into bending engagement with the blank 46 so as to initially bend the same over the mandrel, leaving longitudinally extending side wings at each side of the mandrel, the left-hand wing being longer than the right-hand wing (see Fig. 10). Support of the elongated mandrel by the die-head 86 during descent of bending die 97 precludes flexure of the mandrel during bending of the blank thereover (Fig. 10) by die 97. As soon as this initial bending of blank B is completed, the cam 96 which controls the secondary stamp 82, being shaped to produce a temporary retraction of the latter, operates to withdraw the same, while the cam 30 controlling the movement of stamp member 27 causes the latter to dwell at the downward limit of its movement so as to retain the bending die 97 in position to hold the initially bent blank B against shifting on the mandrel. While the secondary stamp member 82 is thus temporarily retracted, the cams 109 and 114 which control the operation of the respective slide-blocks 99 and 101 and the left and right hand seam lap forming dies 100 and 102 operate to simultaneously advance these dies, thereby bending the wings of blank B inwardly over the underside of the mandrel 53 and into meeting relation, with a free marginal portion of the left-hand wing projecting downwardly beyond the margin of the right-hand wing (see Fig. 11). The cams 109 and 114 are shaped to provide a simultaneous period of dwell adapted to hold the dies 100 and 102 advanced to their last described operative positions, so as to maintain the grip thereof on the formed laps of the blank B. While the dies 100 and 102 thus dwell in lap holding position, the cam 110 which controls the operative movement of the seam lock die 104, is shaped to cause a quick forward and back movement of the latter die effective to turn the free marginal portion of the left-hand wing of blank

B angularly across the free edge of the right-hand wing of said blank B, this occurring while the secondary stamp member 82 remains temporarily retracted (see Fig. 12). The cam 109 has a longer period of dwell timing face than 5 has cam 114, so that die 100 remains in operatively advanced position while die 102 is momentarily retracted. While said die 102 is temporarily retracted, the die 96 controlling the rise of the secondary stamp 82 is shaped to actuate 10 the lifting lever 90 a second time to again thrust upwardly said secondary stamp member 82. Owing to the fact that the push-piece 115 is connected with the slide-block 99 which operates die 100, it follows that said push-piece 115 will remain advanced so long as die 100 occupies its operative advanced position. As a consequence of this the chamfered deflector portion 117 of push-piece 115 lies in the path of the chamfered shoulder 88 of the secondary stamp member 82, 20 so that as the latter rises the second time, said shoulder thereof will ride over said deflector portion 117. The effect of this is to produce a sidewise shift to the right of said die-head 86. Since the way 83 in which the secondary stamp member 82 moves is obliquely and upwardly relieved on its right hand side (see Fig. 4), the sidewise shift above mentioned is not obstructed. This sidewise shift of the secondary stamp member 82, during its second upward movement, deflects die-head 86 sufficiently to cause the same to engage the angularly and laterally bent marginal portion of the left-hand wing of blank B so as to upswing and bend the same around the right-hand wing of said blank B, thus forming 35 an interlock of these parts (see Fig. 13). Upon completion of these operations, cam 96 by its shape effects another downward retraction of the secondary stamp member 82, while at the same time cam 114 controlling the right-hand 40 die 102, again advances the latter in opposition to the still dwelling die 100, thereby to force the parts of the interlock, formed as above described, tightly together (see Fig. 14). If there is any tendency of the die-head 86, by reason of friction, 45 to stick against downward retraction, the advance of the push-piece 118, which moves in company with the die 102, will cause the chamfered end of said push-piece 118 to engage the shoulder 89 of secondary stamp member so as to positively 50 force the same downward out of the path of the advancing die 102. Preferably, the faces of dies 100, 102 are so inclined that the seam elements are displaced from vertical alignment with the axis of the secondary stamp member 82 and inclined downwardly to the right as viewed in Fig. 14. Upon completion of the tightening together of the formed seam lap interlock, the dies 100 and 102 are retracted finally to normal initial positions, whereupon the cam 96 by its shape 60 effects a third up and down movement of the secondary stamp member 82, whereby, on its upward movement, the die-head 86 engages the tightened seam lap interlock and folds the same from the position shown in Fig. 14 to the position 65 shown in Fig. 15. Formed in the underside of the mandrel 53 is a depressed channel or groove G. When the upward movement of die-head 86 folds over the seam lap interlock, the latter is also pressed into said channel or groove G, where- 70 by its outer face is brought flush with the cylindrical surface of the produced cathode tube. It will be observed that during the above-described tube forming and seaming operations, the stamp member 27 dwells in downwardly moved position, 75

thereby retaining the bending die in supporting relation to the blank B and mandrel 53 throughout the performance of said operations. Upon completion of the tube forming and seaming, the 5 stamp member 27 is timed to again rise subject to a repetition of the said operations upon a succeeding blank.

While the stamp member 27 is rising, the cam 59 which controls the longitudinal reciprocation 10 of the mandrel 53 operates first to retract the mandrel and then to return it to normal initial position. The retractive movement of the mandrel slides the same rearwardly through the formed and seamed cathode tube, which cannot 15 move rearwardly therewith by reason of the abutment of its rearward end against the forward end of the die member 35. Due to the frictional engagement the cathode tube with the mandrel, when said mandrel is again advanced, the cathode 20 tube will advance therewith, and will thus be carried into alignment or register with the finishing dies. In the meantime another blank which has been formed by the cutting and preforming dies is advanced into position on the mandrel, 25 to undergo the tube forming and seaming operations.

When stamp member 27 again descends, the advanced formed cathode tube will be acted upon by the meeting finishing dies 120 and 121, whereby 30 by the cylindrical shape of the cathode tube will be trued. The finishing dies are provided with corresponding seats to also receive, embrace and true up the beads 123 with which the cathode tube is provided. Bending die 97 is also provided 35 with seats to receive and guide the beads 123, when the blank B is initially bent.

Upon repetition of the above described operations, including the reciprocation of the mandrel 53, the retraction of the mandrel will slide the 40 same rearwardly relative to the finished cathode tube, so that as the succeeding formed and seamed cathode tube is advanced to the finishing dies by the forward movement of the mandrel, the finished cathode tube will be advanced beyond the 45 finishing dies. From this it will be seen that the finished cathodes will be advanced step by step toward the free end of the mandrel until finally the mandrel withdraws entirely from the outermost cathode, and the same drops away from the 50 mandrel and is thus discharged from the machine into a suitable collecting receptacle.

In brief, after the machine has been in operation a short time, there is a row of tubes on the mandrel. Each time the mandrel is retracted, 55 the rear end of the last-formed tube of the row, by its engagement with the forward end of die member 35 which acts as a stop, causes all tubes of the row to advance with respect to the mandrel, the first-formed tube of the row falling off 60 the end of the retracted mandrel; upon reverse movement of the mandrel all of the remaining tubes of the row on the mandrel advance with respect to the dies; the last-formed tube moves with the mandrel beyond the blank-bending and 65 seam-forming dies to permit the next blank to be bent into a tube and, in the specific machine shown, is positioned with respect to the finishing dies.

It will be obvious that although the machine 70 is especially adapted for the automatic production of cylindrical cathodes, it may be also employed for making lock-seamed tubular structures for various other purposes.

I am aware that many changes could be made 75 in the above described mechanism, as well as in

the details of its general construction and in the mechanisms and parts thereof without departing from the scope of this invention. It is therefore intended that all matter contained in the above description or shown in the accompanying drawings shall be interpreted as illustrative and not in a limiting sense. 5

I claim:

1. In a machine for the purposes described, the combination of blanking dies, means for effecting operation of said blanking dies, a mandrel extending beyond said blanking dies, means to discharge a blank from said blanking dies to said mandrel, means to position and hold the discharged blank in operative relation to said mandrel, a blank bending die above said mandrel, means for moving said blank bending die toward and from said mandrel, a vertically reciprocable die below and movable toward and from said mandrel, opposed transversely movable seam lap forming dies cooperative with said mandrel, a transversely movable seam lock forming die, means for actuating said seam lap and seam lock forming dies in cooperative timed relation subsequent to the operation of said blank bending die, and means to actuate said vertically reciprocable die in cooperative timed relation to the movements of said blank bending die and said seam lap and seam lock forming dies to complete the seam interlock. 30

2. In a machine for the purposes described, the combination of blanking dies, means for effecting operation of said blanking dies, means to feed stock subject to the action of said dies, a mandrel extending beyond said dies, means to discharge a blank from said dies to said mandrel, means to position and hold the discharged blank in operative relation to said mandrel, a blank bending die above said mandrel, means for moving said blank bending die toward and from said mandrel, a vertically reciprocable die below and movable toward and from said mandrel, opposed transversely movable seam lap forming dies cooperative with said mandrel, a transversely movable seam lock forming die cooperative with 40 said mandrel, means for actuating said seam lap and seam lock forming dies in cooperative timed relation subsequent to the operation of said blank bending die, means to actuate said vertically reciprocable die in cooperative timed relation to the movements of said blank bending die and said seam lap and seam lock forming dies to complete the seam interlock, and means cooperative with said mandrel operative to effect discharge of the finished work therefrom. 55

3. In a machine for the purposes described, the combination of blanking dies, means for effecting operation of said blanking dies, means to feed stock subject to the action of said dies, a mandrel extending beyond said dies, means to discharge a blank from said dies to said mandrel, means to position and hold the discharged blank in operative relation to said mandrel, a blank bending die above said mandrel, means for moving said blank bending die toward and from said 60 mandrel, a vertically reciprocable die below and movable toward and from said mandrel, opposed transversely movable seam lap forming dies cooperative with said mandrel, a transversely movable seam lock forming die cooperative with 65 said mandrel, means for actuating said seam lap and seam lock forming dies in cooperative timed relation subsequent to the operation of said blank bending die, means to actuate said vertically reciprocable die in cooperative timed relation 70

75 in the above described mechanism, as well as in

- to the movements of said blank bending die and said seam lap and lock forming dies to complete the seam interlock, finishing dies beyond said blank bending and seam forming dies, means 5 for effecting operation of said finishing dies, and means to longitudinally reciprocate said mandrel whereby the work is fed from the latter dies to said finishing dies and from said finishing dies to eventual discharge from the free end of said 10 mandrel.
4. In a machine for the purposes described, the combination of blanking dies, means for effecting operation of said blanking dies, means to feed stock subject to the action of said dies, a mandrel extending beyond said blanking dies, means 15 to discharge a blank from said dies to said mandrel, means to bend the blank transversely over said mandrel, a plurality of forming dies cooperative with said mandrel and operative upon the 20 longitudinal marginal portion of the bent blank, means for actuating said forming dies in cooperative timed relation subsequent to the operation of said blank bending means, finishing dies beyond said blank bending means and forming dies,
- 25 means for effecting operation of said finishing dies, and means to longitudinally reciprocate said mandrel whereby the work is fed from the latter dies to said finishing dies and from said finishing dies to eventual discharge from the free end of said 30 mandrel.
5. In mechanism for the purposes described, the combination of a primary stamp member, means for effecting vertical reciprocation of said primary stamp member, an upper die block carried by said stamp member, a fixed bottom die block, blanking dies comprising a stationary die member on said bottom die block and a movable die member carried by said upper die block, means to feed stock subject to the action of said 35 blanking dies, a mandrel extending forwardly from said stationary die member and between said die blocks, means to discharge a blank from said blanking dies to said mandrel, means to position and hold the discharged blank in operative 40 relation to said mandrel, a blank bending die carried by said primary stamp member, a vertically reciprocable secondary stamp member below said mandrel, said secondary stamp member having an upwardly projecting die-head, opposed 45 transversely movable seam lap forming dies mounted on said bottom die block, a transversely movable seam lock forming die also mounted on said bottom die block, means for actuating said seam lap and seam lock forming dies and said 50 secondary stamp member die head in cooperative timed relation subsequent to the operation of said blank bending die thereby to interfold and interlock the longitudinal marginal portions of the bent blank to produce on the mandrel a tubular 55 formation closed by an interlocked seam, and means cooperative with said mandrel operative to effect discharge of the finished work therefrom.
6. In mechanism for the purposes described, the combination of a primary stamp member, means 60 for effecting vertical reciprocation of said primary stamp member, an upper die block carried by said stamp member, a fixed bottom die block, blanking dies comprising a stationary die member on said bottom die block and a movable die member carried by said upper die block, means to feed 65 stock subject to the action of said blanking dies, a mandrel extending forwardly from said stationary die member and between said die blocks, means to discharge a blank from said blanking dies to said mandrel, means to position and hold 70

the discharged blank in operative relation to said mandrel, a blank bending die carried by said primary stamp member, a vertically reciprocable secondary stamp member below said mandrel, said secondary stamp member having an upwardly projecting die-head, opposed transversely movable seam lap forming dies mounted on said bottom die block, a transversely movable seam lock forming die also mounted on said bottom die block, means for actuating said seam lap and 10 seam lock forming dies and said secondary stamp member die head in cooperative timed relation subsequent to the operation of said blank bending die thereby to interfold and interlock the longitudinal marginal portions of the bent blank 15 to produce on the mandrel a tubular formation closed by an interlocked seam, finishing dies comprising a stationary female die on said bottom die block beneath said mandrel and a movable male die carried by said upper die block above 20 said mandrel, and means to produce timed longitudinal reciprocatory movement of said mandrel whereby the tubular formations are fed to the finishing dies and from the finishing dies to eventual discharge from the free end of said 25 mandrel.

7. In mechanism for the purposes described, a mandrel, means to position a blank above the mandrel with its longitudinal axis laterally offset relative to the mandrel axis, a vertically reciprocable blank bending die above said mandrel, a vertically reciprocable lower die below said mandrel, opposed transverse dies movable toward and from said mandrel and adapted to complete the bending of a blank around said mandrel and to 30 form the longitudinal marginal portions of said blank into meeting seam laps with one of said laps projecting beyond the other to form a seam lock portion, another reciprocable transverse die movable to turn said seam lock portion across the 35 edge of the other lap, means to deflect at proper time upward movement of said lower die to upturn said seam lock portion along said last named lap, means to actuate said transverse dies in cooperative timed relation, means to produce successive movements of said lower die in timed relation to said transverse die movements to upturn said seam lock as aforesaid and then finally to fold the whole seam structure parallel to the 40 surface plane of the tubularly bent blank, and means to actuate said blank bending die so as to effect a dwell thereof in operative relation to said mandrel during the operations of said transverse dies and said lower die.

8. In mechanism for the purposes described as defined in claim 7, blanking dies to form blanks from sheet stock fed thereto, means for effecting operation of said blanking dies, and timed means for delivering the formed blanks from said dies to the blank positioning means cooperative with the 55 mandrel.

9. In mechanism for the purposes described as defined in claim 7, blanking dies to form blanks from sheet stock, means for effecting operation of said blanking dies, timed means for feeding the stock to said dies, and timed means for delivering the formed blanks from said dies to the blank positioning means cooperative with the 60 mandrel.

10. In mechanism for the purposes described as defined in claim 7, wherein said mandrel is provided on its under side with a receiving channel to receive the seam structure as finally folded by lower die whereby its outer surface is disposed 70 75

flush with the surface plane of the tubularly bent blank.

11. In mechanism for the purposes described as defined in claim 7, finishing dies beyond the blank bending and seam forming dies, means for effecting operation of said finishing dies and means to longitudinally reciprocate said mandrel whereby the tubularly bent and seamed blank is fed from the latter dies to said finishing dies, and from said finishing dies for final discharge from the free end of said mandrel.

12. In mechanism for the purposes described as defined in claim 7, means to retract and advance the mandrel upon completion of the blank bending and seam forming operations, and means to hold the bent and seamed blank against retraction with the mandrel whereby the same is advanced away from the blank bending and seam forming dies and eventually discharged endwise from the mandrel end.

13. In mechanism for the purposes described, blanking and cutting dies to form blanks from sheet metal stock fed thereto, said blanking and cutting dies having means to form at least one suitably located raised transverse bead on the body of said blank, means for effecting operation of said blanking and cutting dies, a mandrel, an initial reciprocable blank bending die, timed means for delivering the formed blank from said blanking and cutting dies onto said mandrel subject to the operation of said initial blank bending die, additional blank bending and seaming dies cooperative with said initial blank bending die and mandrel, means for timing the relative operations of said bending and seaming dies, timed means to retract and advance the mandrel upon completion of the blank bending and seam forming operations, and means to hold the bent and seamed blank against retraction with the mandrel whereby the same is advanced away from the blank bending and seam forming dies and eventually discharged endwise from the mandrel end.

14. In mechanism for the purposes described as defined in claim 13, timed means for automatically feeding metal stock to said blanking and cutting dies.

15. In mechanism for the purposes described, blanking and cutting dies to form blanks from sheet metal stock fed thereto, said blanking and cutting dies having means to form at least one suitably located raised transverse bead on the body of said blank, means for effecting operation of said blanking and cutting dies, a mandrel, an initial reciprocable blank bending die, timed means for delivering the formed blank from said blanking and cutting dies onto said mandrel subject to the operation of said initial blank bending die, additional blank bending and seaming dies cooperative with said initial blank bending die and mandrel, means for timing the relative operations of said bending and seaming dies, finishing dies beyond the blank bending and seaming dies, means for effecting operation of said finishing dies, timed means to retract and advance the mandrel upon completion of the blank bending and seam forming operations whereby the bent and seamed blank is advanced from said bending and seaming dies to said finishing dies and from the latter to eventual discharge endwise from the mandrel end.

16. In mechanism for the purposes described as defined in claim 15, timed means for automatically feeding metal stock to said blanking and cutting dies.

17. A machine comprising a mandrel, a blank-bending die disposed on one side of said mandrel, movable structure disposed on the opposite side of said mandrel, means for moving said bending die toward and from said mandrel, mechanism for feeding between said die and said mandrel a blank to be bent about said mandrel by said die during its movement toward said mandrel, which mandrel is of such dimensions that flexure thereof normally would occur during said bending of the blank, mechanism for moving said structure toward and from said mandrel timed to engage the mandrel to support it against flexure during bending of the blank by said die, means for reciprocating said mandrel axially while said die and said structure are away therefrom, and structure engaging the bent blank, during axial movement of the mandrel in one direction, subsequent movement of the mandrel in opposite direction carrying the bent blank beyond said die.

18. A machine for making tubes comprising a mandrel, means for bending blanks in succession over said mandrel and to fold margins of the successive blanks to form a row of lock-seam tubes on said mandrel, intermittently operated means for supporting said mandrel during the bending and folding of the blanks, means for reciprocating said mandrel axially while unsupported by said intermittently operated means, and means engaging, during axial movement of the mandrel in one direction, the last-formed tube of said row to effect discharge from the mandrel of the first-formed tube of the row, subsequent movement of the mandrel in opposite direction carrying the remainder of the row of tubes beyond said bending and folding means.

19. A machine comprising a mandrel, a blank-bending die disposed on one side of said mandrel, which mandrel is of such dimensions that flexure thereof normally would occur during bending of a blank thereover, movable structure disposed on the opposite side of said mandrel, mechanism for feeding a blank between said die and said mandrel, means for moving said die toward said mandrel to bend the blank, for providing a dwell of said die upon termination of its bending operation, and for subsequently retracting the die from said mandrel, seam-forming dies, means for effecting operation of said seam-forming dies upon the bent blank during said dwell of said blank-bending die, and mechanism for moving said structure to engage said mandrel to support it against flexure during bending of the blank by said blank-bending die and for retracting said structure away from said mandrel before operation upon the blank of said seam-forming dies.

20. A machine comprising a mandrel having a groove extending lengthwise thereof, a blank-bending die disposed on the side of said mandrel opposite said groove, means for moving said die toward and from said mandrel, mechanism for feeding between said mandrel and said die a blank to be bent about said mandrel by said die, said mandrel having such dimensions that flexure thereof normally would occur during said bending of a blank, seam-forming dies, means for effecting operation of said dies upon the bent blank to form a seam, structure disposed on the grooved side of said mandrel, and mechanism for moving said structure toward said mandrel to engage said mandrel to support it against flexure during operation of said blank-bending die, to retract said structure from the path of said seam-

- forming dies, and for operating said structure subsequent to operation of said seam-forming dies, to press the seam into said groove.
21. A machine for making electrodes for therm-
5 ionic tubes comprising blanking and beading dies for making beaded electrode blanks, means for operating said dies, a mandrel of dimensions suited for formation thereon of thermionic tube electrodes, means for intermittently reciprocating
10 said mandrel axially, a blank-bending die, means for feeding the beaded blanks from said first-named dies to position between said mandrel and said blank bending die, means for moving said blank bending die toward and from said mandrel
15 to bend the beaded blanks in succession about said mandrel while it is stationary, and means for restraining the bent blank from movement with said mandrel during one direction of its reciprocation.
- 20 22. A machine comprising a mandrel of dimensions suited for formation thereon of thermionic tube electrodes, mechanism for intermittently reciprocating said mandrel axially, a blank-bending die, a finishing die, mechanism for feeding an
25 electrode blank between said bending die and said mandrel, means for moving said dies toward and from said mandrel, and means for restraining the bent blank during movement of said mandrel in one direction to effect slip thereof with respect
30 to the mandrel to extent sufficient to position said bent blank on the mandrel, upon reverse movement thereof, beyond said blank bending die and in position for operation thereon of said finishing die.
- 35 23. A machine for making tubes which comprises means for bending sheet-metal blanks in succession over a mandrel to form thereon a row of tubes, a finishing die, means for reciprocating said mandrel axially, and means for holding the
40 last-formed tube of said row from movement with the mandrel in one direction to effect discharge from the mandrel of the first-formed tube of the row and to position a bent blank for operation thereon of said finishing die.
- 45 24. A machine comprising a mandrel of such dimensions that flexure thereof normally would occur during bending of a blank about it, a blank-bending die, means for moving said die toward
50 said mandrel to bend a blank, for providing a dwell of said die upon termination of its bending operation, and for subsequently retracting the die from said mandrel, seam-forming die structure, cam means rotating in timed relation to said blank-bending die for effecting operation of said
55 seam-forming die structure upon the bent blank during said dwell of the blank-bending die, mandrel supporting structure, and means for moving said structure temporarily to engage said mandrel to support it against flexure during bending
60 of the blank and for retracting said structure before operation upon the blank of said seam-forming die structure.
25. A machine comprising a mandrel extending freely beyond a support for one end thereof and
65 of such dimensions that flexure thereof normally would occur during bending of a blank about it, a reciprocable blank-bending die having a recess for embracing the mandrel, means for positioning a blank between said mandrel and said die, means
70 for moving said die toward said mandrel to bend the positioned blank and for subsequently retracting the die, and means for precluding flexure of the mandrel during the blank-bending operation comprising a member extending parallel with said
75 mandrel and whose width is not greater than the

width of said recess, and means for reciprocating said member in alignment with said die on the side of said mandrel opposite said die and timed to provide for engagement of said member with said mandrel to support it against flexure during bending of the blank.

26. A machine comprising a mandrel of such dimensions that flexure thereof normally would occur during bending of a blank about it, a blank-bending die, means for moving said die toward
10 said mandrel to bend a blank and for subsequently retracting the die, a mandrel-supporting member, cam-controlled mechanism for moving said member toward and from said mandrel to effect support of the mandrel against flexure during bending of the blank by said die, cam-controlled means for reciprocating said mandrel axially while said die and said member are retracted therefrom, and stop structure for restraining the bent blank during axial movement of the mandrel in one
15 direction.

27. A tube-forming machine comprising a cylindrical mandrel extending freely from a support for one end thereof and of such dimensions that flexure thereof normally would occur during bending of a blank about it, a blank-bending die, means for moving said die toward said mandrel to bend the blank, the wings of the bent blank extending beyond the mandrel, a pair of dies movable in a plane substantially tangent
25 to a surface of said mandrel for bending the wings of the bent blank, a reciprocable member, and means for moving said member to engage the mandrel to support it against flexure during bending of the blank by said blank-bending
30 die and for retracting said member before operation of said wing-bending dies.

28. A machine for forming tubes of small diameter from sheet metal blanks comprising a mandrel, a blank-bending die on one side of said
40 mandrel, mechanism for feeding a blank between said die and said mandrel, means for moving said die toward one side of said mandrel to bend the blank substantially to U-shape about said mandrel and for thereafter withdrawing said die,
45 said mandrel having such small dimensions as materially to flex when unsupported under pressure thereon by said blank-bending die, mandrel-supporting structure on the side of said mandrel opposite to aforesaid one side thereof, and mechanism for moving said supporting structure toward and from said mandrel and timed to bring said structure into position to support said mandrel against flexure during and by the blank-bending action of said die.

29. A machine for making beaded tubular electrodes of small diameter comprising blank-cutting and beading dies, means for feeding strip metal stock to said dies, means for effecting operation of said dies to form severed beaded blanks, a mandrel, a blank-bending die, means for transferring beaded blanks in succession from said cutting and beading dies to position between said mandrel and said blank-bending die, means for actuating said blank-bending die
65 to bend each blank in succession around one side of said mandrel substantially to U-shape, said mandrel having such small dimensions as materially to flex when unsupported under pressure thereon by said blank-bending die, means
70 including said blank-bending die to bend each blank in succession around said mandrel to form a circumferentially beaded tube, and to form a lock-seam from unbeaded marginal portions of the blank, and to lock the seam, mandrel-sup-
75

porting structure on the side of said mandrel opposite to aforesaid one side thereof, mechanism for moving said supporting structure toward said opposite side of said mandrel and timed to bring said structure into position to support said mandrel against flexure during and by the action of said blank-bending die in bending the blank to aforesaid U-shape, and means for sliding the circumferentially beaded tubes along said mandrel.

5 10 30. A machine for forming tubes of small diameter from sheet metal blanks comprising a mandrel, a blank-bending die, means for moving said die toward said mandrel to bend a blank

around one side thereof into substantially U-shape and for subsequently retracting said die from said mandrel, said mandrel having such small dimensions as materially to flex when unsupported under pressure thereon by said blank-bending die, mandrel-supporting structure, and cam structure operating in timed relation to said die for moving said supporting structure temporarily into engagement with the side of said mandrel opposite to aforesaid side to support it 10 against flexure during said bending, and for subsequently retracting said supporting structure from said mandrel.

5 ADOLF HASLAUER.
